UNITED STATES PATENT OFFICE.

FREDERICK WILLIAM SMITH, OF NORTH TONAWANDA, NEW YORK, ASSIGNEE TO
SMITH ORGAN COMPANY, INC., OF NORTH TONAWANDA, NEW YORK, A CORPORATION OF NEW YORK.

TRACKER-BOARD FOR SELF-PLAYING MUSICAL INSTRUMENTS.

1,111,328.

Specification of Letters Patent. Patented Sept. 22, 1914.

Original application filed September 16, 1911, Serial No. 649,772. Divided and this application filed June 26, 1913. Serial No. 775,889.

To all whom it may concern:

Be it known that I, FREDERICK WILLIAM SMITH, a citizen of Great Britain, who has made application to become a citizen of the United States, residing at North Tonawanda, county of Niagara, and State of New York, have invented certain new and useful Improvements in Tracker-Boards for Self-Playing Musical Instruments, of which the following is a specification.

This invention relates to tracker-boards for self-playing musical instruments.

The present application is a division of my copending application on automatic players, filed September 16, 1911, Serial No. 649,772.

This invention consists of a tracker-board having, in addition to the usual note openings, a master opening and controlling openings arranged in a novel manner and adapted, in connection with a perforated music sheet, for the control and playing of one or more organs, pianos, or other musical instruments.

The tracker-board is intended and adapted for use in connection with any system of connections and devices whereby a suitably perforated music sheet passing over the tracker-board may be utilized by the simultaneous coincidence or registry of the perforations in said sheet with the master opening, and certain of the controlling openings, to selectively uncover the controlling openings, and, through the system of connections or devices employed, selectively control the playing of one or more organs, pianos, or other musical instruments through the medium of the note openings.

The pneumato-electric, electro-pneumatic, and electrical means and devices set forth in my application Serial No. 649,772, filed September 16, 1911, are peculiarly adapted for use in connection with the present improved tracker-board, but the latter is not restricted to such a system and may be employed in connection with any other system and means adapted for use therewith and I do not, therefore, restrict the tracker-board to use in connection with any particular system.

The accompanying drawing is a face view of a portion of a tracker-board provided with openings according to the present invention.

T designates a section of a tracker-board which is provided with the usual playing holes 1' which control the means or devices that sound the musical instrument, whether the latter be an organ or piano and whether electro-pneumatically, pneumatically, or mechanically operated. The holes or openings 1' are one hundred and ten in number more or less as may be required, and all of these holes except those included in the transverse rows T' which appear at 1'' are used as playing holes for sounding the notes on the musical instrument, organ or organs, or piano or pianos. In addition to the playing holes 1', I provide series of other supplemental holes T' which control the action of the musical instrument in such manner as to throw on or off the different organs, pianos, musical devices, or manuals to be played by means of the perforations in the music sheet. The tracker-board has in all two hundred and forty-three holes, more or less, as may be required, the number of holes depending on the size of the instrument and the number of the organs, pianos, or other musical devices to be operated. Of this total of two hundred and forty-three holes, more or less, the playing holes 1' constitute one hundred and ten more or less as required to provide for the different manuals and which are divided between solo and accompaniment. Each series of supplemental holes T' consists of two rows, one row being adapted to throw the organ or musical instrument actions on and the other row to throw them off. The openings 1'', while in line with playing openings 1', are not playing openings but are a part of the supplemental control openings T'.

I provide a separate hole or perforation Z in the tracker-board which is in the nature of a "master hole" for the reason that in controlling the various means used in the system, it controls the master device without whose action the organs, pianos, or other musical instruments cannot be operated. I also provide the single row of main controlling holes T² which includes the hole T³ forming no part of the series of playing or note holes 1'. Except when the master hole or opening Z is uncovered by the music sheet, regardless of what other holes are uncovered, operation and sounding of the musical

instrument or instruments controlled by the tracker-board, cannot occur.

The single row of main controlling holes T^2 , including hole T^3 , controls a plurality 5 of devices at least one of which has to be operated by the uncovering of one of said holes T^2 , or T^3 simultaneously with the uncovering of master hole Z by the music sheet before a note can be sounded by any of the 10 note openings $1'$. The holes of the supplemental series T' are, to illustrate the operation, designated as 2, 2^a ; 3, 3^a ; 4, 4^a ; 5, 5^a ; 6, 6^a ; 7, 7^a ; 8, 8^a ; 9, 9^a ; 10, 10^a ; 11, 11^a , considered from right to left.

15 As long as the master hole Z remains closed, no operations will take place and no notes will be sounded, regardless of how many perforations pass over the different holes in the tracker-board, for the reason 20 that the master device controlled by hole Z controls all other operations of the musical instrument or instruments.

Assuming that a hole in the music sheet coincides with the master hole Z , at the same 25 time a hole in the music sheet registers with the hole 2 of right hand series of holes T' and a hole registers with T^2 conditions are then such that any note on a given organ or piano may be played as soon as a hole $1'$ 30 registers with a hole in the music sheet.

If it is desired to operate the control represented by the hole 2 and also a stop or device which is controlled by the opening 9, the holes in the music sheet will be so timed 35 that one opening will register with 2, another opening with 9, another opening with T^2 , another opening with T^3 , and another opening with the master hole Z . It will be seen that although the hole in the music 40 sheet which is to register with T^3 passes directly over the hole T^4 , no result occurs until it reaches its proper destination for the reason that no actuation of any of the devices controlled by those holes can occur until an 45 opening in the music sheet registers with the master hole Z , whereupon the entire line of main controlling holes T^4 , T^5 , etc. is rendered potential perpendicularly, and then each of the lines of holes horizontally which 50 have been registered with holes in the music sheet such as T^4 , 2^a , 3, 3^a , 4, 4^a and T^6 , 7, 7^a , 8, 8^a , 9, 9^a , etc. are also ready to act.

In the case of an organ, by way of illustration, it should be understood that the supplemental controlling holes T' , T^2 , do not, in and of themselves, operate the mechanisms in the wind chest which produce the music, but they merely control the switches on the electric switch-board (assuming that 55 the system of my application Serial No. 649772 is used) so as to put the system in condition to receive the electrical current when the proper opening in the music sheet registers with one of the playing holes $1'$ and

the electricity is then conveyed to the proper 65 motor, or perhaps to several motors, in as many separate wind chests, so that several organs will sound, although only one hole of the holes $1'$ has been uncovered. Consequently, one hole of the series $1'$ is made to 70 play a note in all of the separate organs, or one or more of those organs may be selected, as desired.

The holes T' are used for controlling stops or swell shutters if the tracker-board is used 75 with an organ, or for controlling other musical control devices if used with a piano or other instrument. Any of the holes of series T' can be used, or an entire set in all of said series, but no holes of said series T' 80 produce any effect, when uncovered by the music sheet, unless an opening in the music sheet also registers simultaneously with the master hole Z and another music sheet perforation simultaneously registers with one 85 of the holes T^4 , T^5 , etc. in the same horizontal line with the hole or holes of any of the series T' which are open.

In addition to the holes 2, 2^a , 3, 3^a , etc., there are other holes in the series T' which 90 are numbered from 1 to 100, more or less, which may be used for controlling devices of any character, according to the instrument employed, for pulling additional stops on or off, manipulating additional switches or 95 other devices, etc.

Having thus described my invention, what I claim as new and desire to secure by Letters Patent, is:—

1. A tracker-board for self-playing musical instruments, having a row of note openings and, in addition thereto, a master opening lying inside the path of travel of the music sheet and adapted to be opened by perforations therein and which controls the 105 sounding of the notes by the note openings.

2. A tracker-board for self-playing musical instruments, having a row of note openings and, in addition thereto, a row of controlling openings, and a master opening 110 lying inside the path of travel of the music sheet, said master opening and controlling openings being adapted to be opened by perforations therein and to jointly control the sounding of the notes by the note 115 openings.

3. A tracker-board for self-playing musical instruments, having a row of note openings and, in addition thereto, a row of controlling openings extending lengthwise of 120 the tracker-board, another row of controlling openings extending transversely of the tracker-board, and a master opening lying inside the path of travel of the music sheet, said master opening and controlling openings being adapted to be opened by perforations therein and to jointly control the sounding of the notes by the note openings.

4. A tracker-board for self-playing musical instruments, having a row of note openings and, in addition thereto, transversely arranged pairs of rows of controlling openings, and a master opening lying inside the path of travel of the music sheet, said master opening and controlling openings being adapted to be opened by perforations therein and to jointly control the sounding of the 10 notes by the note openings.

5. A tracker-board for self-playing musical instruments, having a row of note openings and, in addition thereto, transversely arranged pairs of rows of supplemental controlling openings, and a single transversely arranged row of main controlling openings.

6. A tracker-board for self-playing musical instruments, having a row of note open-

ings and, in addition thereto, transversely arranged pairs of rows of supplemental controlling openings, a single transversely arranged row of main controlling openings, and a master opening.

7. A tracker-board for self-playing musical instruments, having a row of note openings, a plurality of rows of transversely arranged supplemental controlling openings, a master opening, and an additional single row of main controlling openings.

In testimony whereof, I hereunto affix my signature in presence of two witnesses.

FREDERICK WILLIAM SMITH.
